UNITED STATES PATENT OFFICE.

NAHO TANAKA, OF NEW YORK, N. Y.

TELEPHONE-TRANSMITTER.

1,231,095.

Specification of Letters Patent. Patented June 26, 1917.

Application filed November 11, 1915. Serial No. 60,946.

To all whom it may concern:

Be it known that I, NAHO TANAKA, a subject of the Emperor of Japan, residing at New York, in the county of New York and State of New York, have invented new and useful Improvements in Telephone-Transmitters, of which the following is a full, clear, and exact description.

This invention relates to improvements in variable resistance devices for application particularly to telephone transmitting apparatus, for the purpose of increasing the efficiency of the apparatus in such manners that the effective cross section of the variable resistance means is enlarged in order to enable the instruments advantageously to carry heavier currents without injury thereto or to increase the resistance variability thereof, while the apparatus are similarly effective with low battery currents, and that the original voice and sound may be transmitted with least or no modification.

I adapt the diaphragm or other vibrator of such an apparatus to vibrate simultaneously at the central and outer portions thereof by employing certain flexibly mounting means for the vibrator and other moving parts, and construct the diaphragm or vibrator as light as possible, so that the inertia thereof will not be detrimental in operation, and also in order to increase the electrode surface, I extend the carbon contact means to the outer portion of the vibrator preferably in a plural form.

The particular object of the invention is to provide telephone transmitters which have greater carrying capacity of battery power or greater variability of resistance, and with which voice and sound are more faithfully transmitted than with ordinary instruments.

Further object is to provide apparatus of the class named which are durable and reliable without becoming packed.

With the above and other objects in view, my invention resides in the peculiar combination and arrangement of parts, and comprises certain detail of constructions, as will be hereinafter more fully described, illustrated, and claimed.

The invention will be best understood from the following description, taken in connection with the accompanying drawings as reference, forming a part of this specification. However, I desire to have it understood that the apparatus shown here-

in are merely illustrative, and that therefore I do not confine myself to any strict conformity with the showing of the drawings, but such changes and modifications may be made, when desired, as to fall within the scope of the invention as claimed.

In the drawings, similar numerals of reference indicate similar parts in all the views, and in which—

Figure 1 represents a vertical central section of a transmitter embodying my invention,

Fig. 2 shows a modification of the apparatus, my improvements applied thereto, being a similar view to Fig. 1.

Fig. 3 is a back view of the vibrator part of Fig. 2, and

Fig. 4 is a front view of the back electrode part of the same.

Referring to the drawings, the numeral 10 designates a bridge or cup clamped with a front piece 11 constituting a casing. The front piece has a preferably large opening which is screw-threaded to receive an usual mouth-piece 12. This opening is closed by a film 18 of moisture proof material to protect the working parts within the casing.

A diaphragm or vibrator 13 which is located in the front portion of the casing carries as a part thereof front electrodes 14 on somewhat raised portions, clamping an elastic sheeting 17 therebetween, such as mica sheeting (see Fig. 1) and is shown in Fig. 2 in a form of plurally cup-shaped or depressed disk of suitable solid material, for instance stamped out of metal, preferably aluminum, having thin carbon electrodes 14 (soldered thereon after electro-plating), as parts thereof at the bottoms of the depressed portions which are extended to the outer portion of the vibrator. I herein employ "a vibrator" to mean "a diaphragm or other vibrator," as it may not be proper to call it a diaphragm in such a construction, when the edge portion thereof is not fixed and it is not a plain disk, as later will be referred to.

At the rear of the vibrator 13 in parallel therewith is disposed an electrode support or bearing plate 15 (of insulating material in the present instances, or of carbon or metal when suitable to use) which is depressed or shaped at front so as to form a number of cups or chambers, having back electrodes 16 of carbon in the cups or chambers (Fig. 1). The back electrode part 15

is attached to the sheeting 17, so that the necessary relative movement between the vibrator 13 and the back electrode part 15 is permitted by the flexing of the sheeting, 5 each front electrode being arranged to confront one of the back electrodes 16 in the chamber which is closed thereby. In Fig. 2 back electrodes are placed in parallel with the front electrodes 14 in a manner to close 10 the cup portions to form a plurality of chambers a flexible sheeting 17 connecting them to the vibrator as in Fig. 1. In the electrode chambers thus formed, carbon granules or balls 19 are disposed to 15 fill the spaces partly or fully in contact with the electrodes therein. The combined electrode surface is made large as much as permissible to increase the effective cross section of the carbon cells, as far as the 20 operative advantages are concerned. The back electrode part 15 is preferably, though not necessarily, secured resiliently to the casing by means of springs 20. The peripheral edge of the sheeting 17 is held between the 25 cup 10 and the front piece 11, flexibly connecting the working parts and the casing. By employment of the springs, the connection between the sheeting 17 and the back electrode part 15 may be omitted, the leakage 30 of the carbon being prevented by the narrowness of the distance, if any, left between, or by the close contact between them each pressing toward the other. Also the working part may be wholly supported by 35 the springs when desired. In Fig. 2, the working parts are cushioned at the front by a ring washer 21 of soft elastic material such as felt or pneumatic rubber, and at the back by a similar washer 22 or spring 20, 40 as in Fig. 1.

As adjusting means of pressure on the washers or cushions as well as on the granular carbon, an adjusting plate 24 is provided, having an arm 25 at the center which 45 passes through the tubular portion 23 of the cup or bridge 10, and fits almost snugly in the tube being movable only in the direction of the tube axis, when the screw on the tube is loosened.

50 While I have shown and described herein some of modifications of the apparatus and of parts thereof, it must be understood that the construction and arrangement of parts disclosed in and described for one form are 55 similarly applicable to the other. And although I have shown herein two forms of modification each having four carbon contact cells, the form and number of the carbon cells are of course susceptible to changes, 60 whenever desired.

In the construction as above upon the incidence of vocal waves on the vibrator, the action of the variable resistance mediums in varying their resistance will be 65 substantially uniform throughout the whole

cross section thereof, and the vibrator will respond substantially only to the pulsations coming through the mouth piece 12 practically without being molested by the natural vibration thereof and external vibrations. 70

The carbon contact cells may be connected either in multiple-series, in series (provided the vibrator is made of nonconductive material), or in parallel as it is the case when 75 the vibrator and the back support are conductive, and the electrodes are not insulated therefrom. The terminals of the connection are led out to two insulated binding screws (not shown) on the casing. 80

From the foregoing description, taken in connection with the accompanying drawings, the advantages of the construction and arrangement of parts, and the method of operation, in which vocal vibrations are 85 translated into electrical impulses, will be readily apparent without further explanations to those skilled in the art to which this invention appertains.

Having thus described the invention, I 90 claim:

1. In a telephone transmitter, a vibrator having cup-shaped or depressed portions and bearing front electrodes in the said portions, an elastic or flexible sheeting attached 95 thereto, back electrodes attached to the sheeting within the inclosures formed by the sheeting and the said portions and secured together by a plate or disk, a casing holding the peripheral edge of the sheeting, 100 and granular carbon between and in contact with the front and back electrodes.

2. In a telephone transmitter, a vibrator bearing front electrodes, a flexible or elastic sheeting attached thereto, a back electrode 105 part, including back electrodes, shaped and attached to the sheeting so as to form chambers in which the said front and back electrodes are contained, a casing holding the edge of the sheeting, and variable resist- 110 ance mediums disposed in the chambers.

3. In a variable resistance device, the combination of a casing, an elastic sheeting held thereby, and a vibrator and a back electrode part, each including an electrode, 115 shaped and attached to the sheeting so as to be relatively movable and to form therebetween a chamber in which the said electrodes are contained; with a variable resistance medium disposed in the chamber 120 and in contact with the electrodes.

4. In a telephone transmitter, the combination of a casing, a flexible or elastic sheeting held thereby, a vibrator and a back electrode part, both including electrodes, shaped 125 and attached to the sheeting so as to form chambers therebetween which inclose the electrodes, and so as to be in flexible connection, and cushioning means between the back electrode part and the casing; with 130

granular carbon disposed between and in contact with the electrodes.

5. In a telephone transmitter, the combination of a vibrator and a back electrode part, both including electrodes, shaped and disposed so as to form chambers therebetween, a casing, a flexible or elastic sheeting attached to the casing and the vibrator, so that the latter two members are relatively movable, a spring means bridging or connecting the back electrode part and the casing; with carbon balls or grains disposed in the chambers and in contact with the electrodes.

15. 6. In a telephone transmitter, the combination of a vibrator and a back electrode part, both including electrodes as parts thereof, shaped so as to form chambers which inclose the electrodes in pairs, an elastic sheeting attached thereto to flexibly join the said two parts and to close the chambers, and a casing holding the peripheral edge of the sheeting; with variable resistance mediums in contact with the electrodes.

25. 7. In a telephone transmitter, the combination of front and back vibratory plates, cases or chambers mounted on one of the said plates, primary electrodes attached to the cases or chambers, secondary electrodes attached to the other vibratory plate, each confronting one of the primary electrodes, a casing, an elastic or flexible sheeting held by the casing and attached to the plates so as to flexibly connect them together and to close the cases or chambers; with variable resistance mediums disposed in the cases or chambers in contact with the electrodes therein.

40. 8. In a telephone transmitter, a vibratory plate and a back electrode part shaped and disposed to form chambers therebetween, a yielding washer held between to close the chambers, a casing, an elastic sheeting attached to the vibratory plate and the casing, spring means attached to the back electrode part and the casing, and variable resistance mediums in the chambers.

45. 9. In a telephone transmitter, the combination of a vibratory plate having cup-shaped or depressed portions, a back electrode part, flexibly secured to a support, and an elastic sheeting clamped to the back elec-

trode part and the vibratory plate and disposed so as to form with the said plate 55 chambers which contain the electrodes, with variable resistance material confined in the chambers.

10. In a telephone transmitter, the combination with a casing, a vibrator and a back 60 electrode part both having electrodes in chambers formed therebetween, an elastic sheeting held therebetween and attached to the casing, and variable resistance mediums 65 between the electrodes; of a cushion mounting for the above parts as a whole sufficiently flexible so as to allow the vibrator to vibrate substantially bodily in the intended operation.

11. In a telephone transmitter, the combination with a casing, and resistance varying 70 means for transmitting sound, including a vibratory body, and a back electrode part; of spring members flexibly connecting the vibratory body and the back electrode part 75 to the casing.

12. In a telephone transmitter, the combination with a casing; of front and back vibratory plates, a granular carbon cell carried by one of the plates between them, an 80 elastic sheeting held by the casing at the peripheral edge and attached to the front plate, spring members attached to the casing and the back plate, and a yielding or pliable washer held between the plates. 85

13. In a telephone transmitter, the combination of two vibratory plates, chambers or cases carried by one of said plates as a part thereof and resiliently or flexibly attached to the other, and a support flexibly 90 secured to one of the said plates; with variable resistance mediums in the chambers or cases.

14. In a telephone transmitter, a casing, a front vibratory plate, a back plate the peripheral edge of which is free to vibrate resiliently secured to the casing, carbon cells rigidly carried by one of the said plates, and resiliently attached to the other plate. 95

In testimony whereof I affix my signature 100 in presence of two subscribing witnesses.

NAHO TANAKA.
